(57) **CLAIM**

The ornamental design for four compartment square container, as shown and described.

DESCRIPTION

FIG. 1 is a top isometric view of a four compartment square container showing our new design.

FIG. 2 is a top plan view thereof.

FIG. 3 is a bottom plan view thereof.

FIG. 4 is a front elevation view thereof, the rear elevation view being a mirror image thereof; and,

FIG. 5 is a left side elevation view thereof, the right side elevation view being identical thereof.

The broken line showing of trifurcated designs in FIGS. 1-3 are for the purpose of illustrating portions of the article and form no part of the claimed design.

1 Claim, 5 Drawing Sheets

FIG. 1

FIG. 2

FIG. 3

FIG. 4

FIG. 5
